GASEOUS ELECTRIC DISCHARGE DEVICE

Willem Uyterhoeven, Cornelis Verburg, and
Eduard G. Dorgelo, Eindhoven, Netherlands,
assignors to General Electric Company, a cor-
poration of New York

Application June 26, 1934, Serial No. 732,490
In the Netherlands July 4, 1933

6 Claims. (Cl. 176—124)

The present invention relates to gaseous electric discharge devices generally and more particularly the invention relates to starting and operating circuits for such devices.

5 The starting voltage of gaseous electric discharge devices is higher than the operating voltage thereof. The higher starting voltage can be supplied to such devices by connecting a choke-coil in series therewith and a condenser in parallel therewith, the choke-coil and the condenser being so proportioned with respect to each other that they are in resonance for the fundamental frequency of the alternating current source to which said discharge device is connected. 10 Such a circuit is not satisfactory for gaseous electric discharge devices having thermionic electrodes, i. e., electrodes which are electron emitting when heated, because the condenser shortens the life of this type of electrode, 15 which causes rapid depreciation of the gaseous electric discharge device, and the discharge itself is very irregular.

The object of the present invention is to provide a starting and operating circuit for a gaseous electric discharge device, said circuit comprising a choke-coil connected in series with the device and a condenser connected in parallel with the device whereby the above disadvantages are avoided. Still further objects and advantages 20 attaching to the device and to its use and operation will be apparent to those skilled in the art from the following particular description.

We have discovered that the above object is attained when the condenser and the choke-coil 25 are in resonance for a higher harmonic (preferably the third harmonic) rather than for the fundamental frequency of the alternating current source for the discharge device. The irregularity in the discharge and the harmful effects on the 30 thermionic electrode is eliminated in such a circuit. When the voltage of the current source has no higher harmonics special means can be used in the circuit for creating higher harmonics. A choke-coil having a highly saturated iron core, 35 which type of choke-coil generates higher harmonics, particularly the third harmonic, is useful for this purpose.

When desired, an auxiliary gaseous electric discharge device is connected into the above described circuit to generate the higher harmonics or an auxiliary discharge path is provided in the main gaseous electric discharge device for the same purpose. In the latter arrangement the auxiliary gaseous electric discharge not only produces the higher harmonics but also ionizes the

5 gaseous filling in the discharge device to facilitate the starting of the main discharge therein. When the gaseous electric discharge is of the type having two main discharge supporting thermionic electrodes in spaced relation, an auxiliary electrode is mounted adjacent each of said thermionic electrodes and each of said auxiliary electrodes is connected to a condenser which is tuned to a choke-coil for a higher harmonic. The condenser is connected to the main electrode remote from the auxiliary electrode connected to said condenser. When desired one condenser, 10 connected between the two auxiliary electrodes, is used.

When an auxiliary gaseous electric discharge 15 device is used to produce the higher harmonics said auxiliary discharge device is utilized to cut the condenser out of circuit during the operation of the main discharge device, when desired, as disclosed in the copending application Serial 20 Number 728,765, filed June 2, 1934, the inventor being Lourens Blok. In the application referred to the choke-coil is connected in series with the main discharge device, a condenser is connected in parallel to said main discharge device and an auxiliary gaseous electric discharge device is connected in series with said condenser. The auxiliary gaseous electric discharge device is startable on the voltage of the current source for the 25 circuit but the voltage applied thereto after the main discharge device has been started into operation is insufficient to maintain the auxiliary device in operation and the condenser is cut out of circuit. Other means, such as a bi-metallic element, is used to cut the condenser out of circuit during the operation of the main discharge device, when desired. 30

In the drawing accompanying and forming part of this specification several embodiments of the invention are shown, in which,

40 Fig. 1 is a schematic view of one embodiment of the invention,

Fig. 2 is a similar view of another embodiment of the invention,

Fig. 3 is a similar view of still another embodiment of the invention, and

Fig. 4 is a similar view of another embodiment of the invention.

Referring to Fig. 1 of the drawing the new and novel starting and operating circuit consists of a 50 tubular gaseous electric discharge device 1 having a gaseous filling therein, such as neon, and having a thermionic electrode 2 at each end thereof. Said electrodes 2 consist of a coiled filament, such as a tungsten or nickel filament, coated or im- 55

pregnated with an electron emitting material, such as barium oxide. Said discharge device 1 is connected to the terminals 3 of an alternating current source of commercial voltage, such as 110 or 220 volts. A choke-coil 4 is connected in series with said discharge device 1 and a condenser 5. 5 is connected in parallel with said device 1. The condenser 5 and the choke-coil 4 are of such dimensions with respect to each other that they are in resonance for a high harmonic of the alternating current source. When the frequency of the alternating current source is 50 cycles, for example, the self-inductance of the choke-coil 4 is 0.6 henry and the capacitance of the condenser 10 5 is 1.7 millifarad, when desired.

As pointed out above an auxiliary gaseous electric discharge device 20 is connected in series with said condenser 5 to produce the higher harmonics, when desired. In such an apparatus the auxiliary 20 gaseous electric discharge device 20 is utilized to cut the condenser 5 out of circuit during the operation of said main discharge device 1 and said auxiliary device 20 is startable on the voltage of the current source and inoperable on the voltage applied thereto after said main device 1 has been started into operation.

The embodiment of the invention illustrated in Fig. 2 of the drawing consists of a U-shaped gaseous electric discharge device having main discharge supporting thermionic electrodes 7 and 8 sealed therein at the ends thereof and hollow, open-ended cylindrical auxiliary electrodes 9 and 10 surrounding said main electrodes 7 and 8 respectively. When desired, said auxiliary electrodes 35 9 and 10 are thermionic electrodes. The gaseous filling of said discharge device 6 consists of a rare gas, such as neon, and a difficultly vaporizable material, such as sodium. It is advantageous to provide said lamp device 6 with a heat conservator to reduce the heat radiated by the lamp 6 and thus maintain an effective vapor pressure of the difficultly vaporizable material during the operation of the discharge device. A double walled jacket having the space between the walls thereof evacuated is suitable for this purpose.

The main electrode 7 is connected to said auxiliary electrode 10 through a condenser 11. Similarly the main electrode 8 is connected to the auxiliary electrode 9 through the condenser 12. 50 Said main electrode 7 is connected to one end of the choke-coil 13 and the other end of said choke-coil 13 is connected to a terminal 14 of an alternating current source. The main electrode 8 is connected to the other terminal 14 of said current source.

Two circuits are thus connected in parallel with the main discharge between the main electrodes 7 and 8. One circuit consists of the condenser 12 and the auxiliary discharge between the main electrode 7 and the auxiliary electrode 9 while the other circuit consists of the condenser 11 and the auxiliary discharge between the main electrode 8 and the auxiliary electrode 10. Said choke-coil 13 is connected in series with both of 65 said circuits. Each of said condensers 11 and 12 are of such size with respect to said choke-coil 13 that each of said condensers 11 and 12 and said choke-coil 13 are in resonance for the third harmonic of the alternating current source. The 70 presence of an auxiliary discharge in each of the circuits comprising a choke-coil and a condenser is favorable for generating the third harmonic. The auxiliary discharges between the electrodes 7 and 9, 8 and 10 are not only favorable for generating a third harmonic but also facilitate the

starting of the main discharge between said electrodes 7 and 8 by ionizing the gas therebetween.

The thermionic electrodes of the discharge devices 1 and 6 are heated to an electron emitting temperature by separate heating currents, when desired, or said electrodes are heated to this temperature solely by the discharge, when desired. When said electrodes are heated solely by the discharge the auxiliary discharges in said device 6 serve to heat the electrodes to such temperature. 10

The starting of the main discharge in the above described embodiments of the invention is positive and quick and the difficulties encountered in prior circuits wherein the choke-coil and the condenser are so proportioned that they are in 15 resonance for the fundamental frequency of the alternating current source to which said discharge device is connected are avoided.

The embodiment of the invention illustrated in Fig. 3 of the drawing is similar in all respects to that shown in Fig. 2 except that in this embodiment only one condenser 15 is connected between the auxiliary electrodes 9 and 10. A circuit comprising two discharge paths and the condenser 15 is thus formed which circuit is connected in parallel with the main discharge path between the electrodes 7 and 8.

The embodiment of the invention illustrated in Fig. 4 of the drawing is similar in all respects to that illustrated in Fig. 1 except that in this embodiment the choke-coil is of a different type. The choke-coil in this embodiment of the invention has an iron core having two legs 16 and 17 of different thicknesses having coils 18 and 19 wound thereon, respectively. The leg 16 is considerably 35 thinner than the leg 17. The two coils 18 and 19 of the choke-coil are connected in series and are wound in such manner that the current traversing said coils 18 and 19 produces opposite fluxes in the core. The coil 19 is connected in 40 series with the device 1. After current is applied to the circuit and before the discharge device 1 has started into operation current flows through coil 18 of the choke-coil and the condenser 5 which are connected in series. The leg 16 is of such size that during this period it is highly saturated and a strong third harmonic is produced. After the discharge device 1 has been started into operation a weaker flux is present in the core which is desirable in view of the 50 higher current.

While we have shown and described and have pointed out in the annexed claims certain novel features of the invention, it will be understood that various omissions, substitutions and changes 55 in the forms and details of the circuits illustrated and in their use and operation may be made by those skilled in the art without departing from the broad spirit and scope of the invention, for example, other types of electron emitting electrodes, such as the Hull electrode, or the Pirani electrode are used in the main discharge device, when desired.

What we claim as new and desire to secure by Letters Patent of the United States is:— 65

1. A circuit for starting and operating a gaseous electric discharge device comprising in combination, a condenser connected in parallel with said device, a choke-coil connected in series with said device, a current source for said device, 70 said choke-coil and said condenser being so proportioned with respect to each other that they are in resonance for a higher harmonic of the alternating current source.

2. A circuit for starting and operating a 75

- gaseous electric discharge device comprising in combination, a condenser connected in parallel with said device, an auxiliary discharge connected in series with said condenser, a choke-coil connected in series with said device, a current source for said device, said choke-coil and said condenser being so proportioned with respect to each other that they are in resonance for a higher harmonic of the alternating current source produced by said auxiliary discharge.
- 5 3. A circuit for starting and operating a gaseous electric discharge device comprising in combination, a condenser connected in parallel with said device, a choke-coil connected in series with said device, an auxiliary gaseous electric discharge device connected in series with said condenser, a current source for said first named device, said choke-coil and said condenser being so proportioned with respect to each other that they are in resonance for a higher harmonic of the alternating current source produced by said auxiliary device.
- 10 4. A circuit for starting and operating a gaseous electric discharge device comprising in combination, a condenser connected in parallel with said device, a choke-coil connected in series with said device, an auxiliary gaseous electric discharge device connected in series with said condenser, a current source for said first named device, said choke-coil and said condenser being so proportioned with respect to each other that they are in resonance for a higher harmonic of the alternating current source produced by said auxiliary device, said auxiliary discharge device being startable on the voltage of the current source and inoperable on the voltage applied
- 15 thereto after said main device has been started into operation.
- 5 5. A circuit for starting and operating a gaseous electric discharge device having a pair of main discharge supporting thermionic electrodes and an auxiliary electrode mounted adjacent each of said main electrodes, said circuit comprising in combination, a choke-coil connected in series with said device, a current source for said device and a condenser connected in series with one of the auxiliary discharges in said device, said choke-coil and said condenser being so proportioned with respect to each other that they are in resonance for a higher harmonic of the alternating current source produced by said auxiliary discharge.
- 10 6. A circuit for starting and operating a gaseous electric discharge device comprising in combination, a condenser connected in parallel with said device, a choke-coil connected in series with said device, a current source for said device, said choke-coil having at least two legs of different thickness and a coil wound on each of said legs, said coils being wound in opposing directions and being connected in series, the coil wound 20 on the thinner leg being connected in series with said condenser directly and in series with said device through the coil on the thicker leg, said thinner leg and said condenser being so proportioned with respect to each other that they are in 25 resonance for a higher harmonic of the current source.
